United States Patent Office.

A. J. FELLOWS, OF MERIDEN, CONNECTICUT.

Letters Patent No. 78,272, dated May 26, 1868.

IMPROVEMENT IN TAPE-BOXES.

The Schedule referred to in these Letters Patent and making part of the same.

TO ALL WHOM IT MAY CONCERN:

Be it known that I, A. J. FELLOWS, of Meriden, in the county of New Haven, and State of Connecticut, have invented a new and useful Improvement in Tape-Boxes; and I do hereby declare that the following is a full, clear, and exact description thereof, which will enable others skilled in the art to make and use the same, reference being had to the accompanying drawings, forming part of this specification.

The present invention relates to the catch, by means of which the drum of the box, having the tape wound around it, is held or released, as may be desired.

In the accompanying plate of drawings my improvement in tape-boxes is illustrated—

Figure 1 being an inside face view of a box having it applied thereto, and

Figure 2 a transverse section, taken in the plane of the line α α , fig. 1.

Similar letters of reference indicate corresponding parts.

A, in the drawings, represents the case or box, having arranged within it the drum B, provided with a coiled spring, as in ordinary tape-boxes, C being the tape wound around it, extending out of the box through the slit or opening, D, in the side or edge E. This drum is provided with teeth F, as in ordinary tape-boxes, and with such teeth the spring-catch G engages, that forms the subject of the present improvement.

This spring-catch is made of the general shape shown, and by its end G engages with the teeth to the tape-drum or wheel, while by its other it is fixed over and upon the square portion to the drum-centre spindle H. I, the lever for releasing the catch from the drum-teeth, for which it is only necessary to press it forward.

As my improved catch is not attached to the back of the case or box, it is plainly obvious that rubber, ivory, and other material may be used, which, in the ordinary mode of applying the catch, could not be used.

I claim as new, and desire to secure by Letters Patent—

The catch G, in combination with the toothed drum B, spindle H, lever I, coiled-spring, case A, and tape C, substantially as described for the purpose set forth.

A. J. FELLOWS.
